UNITED STATES PATENT OFFICE.

WILLIAM BERK, OF NEW YORK, N. Y., ASSIGNOR TO AMERICAN AUTO LAMP COMPANY, INC., OF NEW YORK, N. Y., A CORPORATION OF NEW YORK.

DESIGN FOR AN AUTOMOBILE SIGNAL-LAMP CASING.

Application filed July 6, 1925. Serial No. 18,992. Term of patent 14 years.

To all whom it may concern:

Be it known that I, WILLIAM BERK, a citizen of the United States, and a resident of 1072 Bryant Avenue, in the city of New York, county of Bronx, and State of New York, have invented a new, original, and ornamental Design for an Automobile Signal-Lamp Casing, of which the following is a specification, reference being had to the accompanying drawing, forming part of this specification.

The figure is a perspective view showing my new design.

I claim:

The ornamental design for an automobile signal lamp casing as shown.

WILLIAM BERK.
